UNITED STATES PATENT OFFICE.

GEORGE L. CORCORAN, OF ST. LOUIS, MISSOURI, ASSIGNOR TO CHAMPION SHOE MACHINERY COMPANY, OF ST. LOUIS, MISSOURI, A CORPORATION OF MISSOURI.

SEWING-MACHINE.

1,134,033.

Specification of Letters Patent. Patented Mar. 30, 1915.

Application filed December 5, 1910. Serial No. 595,799.

To all whom it may concern:

Be it known that I, GEORGE L. CORCORAN, a citizen of the United States, residing at St. Louis, in the State of Missouri, have invented a new and useful Sewing-Machine, of which the following is a specification.

This invention relates to sewing machines of the wax thread type, and more particularly to the mechanism for controlling the thread for the purpose of setting the stitch and drawing or measuring the supply of thread for the stitches.

In sewing machines which are adapted for sewing work of different thickness, it is desirable and necessary to vary the supply of measured thread in accordance with the thickness of the work, in order that the stitch may be set uniformly.

The objects of this invention, therefore, are to construct thread controlling mechanism in which the thread is measured in accordance with the thickness of the work, and in which the stitches are set uniformly irrespective of the thickness of the work.

Further objects will appear from the detail description taken in connection with the accompanying drawings, in which,

Figure 1 is a side elevation of the head and work support of a sewing machine, showing this invention applied thereto, Fig. 2 is a plan view, Fig. 3 is a side elevation of the opposite side of the machine, certain parts of the mechanism being omitted for the sake of clearness, Fig. 4 is a section of the thread lock, Fig. 5 is another section, but taken at right angles to that of Fig. 4, and Fig. 6 is a transverse section on the line 6—6 Fig. 5.

Referring to the drawings, 10 designates the work support, and 11 the head of a sewing machine, which in this particular instance is of the lock-stitch type. An awl 12 is supported by the awl-bar 13 which reciprocates vertically in the head of the machine and is guided at its upper end by a cross head 14 engaging a guide 15. A hooked needle 16 enters the hole made in the stock S from below. Looper mechanism of well known construction and comprising fingers 17 and 18, is arranged to loop the needle thread around the needle in a manner well known to those skilled in the art. The awl, as well as the needle, shuttle, and looper, are operated by suitable mechanism from a main shaft such as B, through suitable

links and levers as usual in machines of this type. A presser foot 19 is supported by a presser foot bar 20, which is arranged to be moved vertically in bearings in the head. The upper end of the presser foot bar has 60 secured to it a finger 21 the forked end of which engages a guide bar 22 secured to the head. A toe 23, of a lever 24 pivoted at 25 in the head, extends underneath the finger 21, and the opposite end of the lever is connected by a treadle rod 26 to a suitable treadle. The presser foot is normally pressed down on the work by means of a leaf spring 27, and this presser foot can be raised by means of the treadle through the 70 connections shown.

The needle thread T from the main supply 30 passes through a thread lock A, over a guide 31, and through the wax pot 32. An arm 33 is pivoted on the wax pot or to any 75 other suitable part of the machine head, and is under the tension of a spring 34, which normally tends to move the free end of the arm to the right, Fig. 1. Arms 35 and 36 are pivoted to the head of the machine and 80 are provided at their free ends with guides for the thread. The arm 36 is secured to an actuator shaft 37 which has also rigidly secured to it an arm 38 connected by a link 39 to the arm 35. The arms 36 and 38 form 85 together a double arm lever as shown in Figs. 1 and 2, and the arm or lever 35 is actuated from the arm 38 of this lever. By means of this construction the arms 35 and 36 move toward and from each other. The 90 shaft 37 has rigidly secured thereto a pinion or segmental gear 40 which meshes with a toothed segment or segmental gear 41 on one end of a lever 42 pivoted at 42^a in the head. The other end of the lever is connected by a link 43 to a lever 44 which is 95 provided with a cam roll engaging a face cam 45 on the main shaft B.

The thread lock comprises a cylindrical body 50 which is bored and provided with a 100 securing flange 51, so that the lock can be inserted into a hole in the head and secured in position by means of screws passing through the flange. The upper end of the lock body is threaded to receive a knurled sleeve 52 and a knurled lock nut 53. A knurled head 54 is mounted on a shank 55, the end of which is threaded to receive a collar 56 which affords an abutment for one 105 end of a spring 56^a, the other end of which 110

bears against a shoulder formed in the lock body. The shank is provided with a hardened end 57, and its upper end with a slot 58 for the thread. The collar 56 is locked 5 against turning by means of a screw 59 engaging a slot 59^a in the lock body, and the head 54 is provided for a similar purpose with a guide pin 60 engaging a socket in the lock body. This guide pin is screwed into 10 the head 54 and locked in position by means of a lock nut 61. The cooperating faces of the plunger head 54 and sleeve 52 are coned as shown in the drawing for the purpose of gripping the thread. A tappet 62 slides in 15 the bore of the lock body and is prevented from dropping out by means of a screw 63 engaging a slot 64^a. The upper end of this tappet is inclined to correspond with the incline on a sliding wedge 64 which is guided 20 by the slots 64^a. The wedge 64 is connected by a link 65 to one arm of a lever 66 pivoted at 25. The other arm of the lever is connected by a link 67 to an arm 68 secured to and projecting rearwardly from the upper 25 end of the presser foot bar, this arm being preferably a part of or integral with the finger 21. The tappet 62 is arranged to be engaged by the end 69 of the lever 42.

A tension device is arranged between the 30 lock and the thread supply so as to deliver the thread to the lock under tension. This tension device comprises a bracket 70 secured to the lock body and provided with eyes 71 and 72 for receiving and guiding the 35 thread. The thread is gripped between a pair of tension plates or disks 73 pressed together by means of a spring on a threaded shank secured to the bracket, and the tension of this spring can be regulated by 40 means of a wing nut 75.

The arms 35 and 36 constitute together a take-up mechanism (or take-up members) the function of which is to take up the thread, set the stitch, and give up the thread 45 to the needle and the shuttle in the formation of the stitch. In this case, however, the take-up mechanism performs an additional function, namely that of drawing or measuring the thread for the next stitch. This is 50 accomplished by constructing the take-up mechanism so that it has two actions or movements, one of which is the take-up and setting action, and the other of which is a thread drawing or measuring action. In 55 the preferred form the lock is maintained closed until the stitch is set and then it is opened to permit the take-up mechanism in the last part of its movement to draw or measure the thread for the next stitch.

60 The lock is closed to grip the thread between the plunger head 54 and the collar 52 by means of the spring 56^a, and the thread is released by the engagement of the end 69 of the lever 42 with the tappet 62. The 65 raising of the tappet causes the wedge 64 to

be moved upwardly to engage the end 57 of the plunger so as to raise it against the tension of its spring 56^a. Both the lock and the take-up mechanism are operated from the lever 42 so that they are interconnected 70 to operate in timed relation.

Assume that the stitch has been formed and that the arms 35 and 36 have moved toward each other so as to give up the thread during the formation of the stitch. As the 75 arms 35 and 36 again move away from each other, the thread will be taken up and the stitch will be set against the tension of the spring 34, the thread being at this time firmly gripped by the thread clamping or 80 gripping members 52 and 54 of the thread lock A. During the latter part of this movement of the arms 35 and 36 the lever 42 will engage the tappet 62 to open the lock A and permit thread for the next stitch to 85 be drawn by the take-up mechanism. Thereafter the lock will be closed by its spring and the thread will be again given up by the take-up mechanism during the formation of 90 the next stitch.

It will be evident that the measured supply of thread must be varied in accordance with the thickness of the stock. This is accomplished by providing an adjustable work engaging member which varies in its position in accordance with the thickness of the work, and controls the thread drawing action of the above described mechanism. In the specific embodiment shown, the presser foot is movable and adjustable and is interconnected with the sliding wedge 64. It will be seen that there is a lost motion connection between the tappet 62 and wedge 64, and the end 57 of the plunger. Now by varying the position of the wedge, the amount of such lost motion can be varied as will be obvious by referring to Figs. 4 and 5. Thus if the wedge is moved to the left, Fig. 4, the amount of lost motion will be decreased, and if moved to the right, will be increased. A decrease in the lost motion will cause the lock to be opened earlier in the take-up and lock setting movement of the take-up mechanism, so that the amount of thread drawn or measured is increased, keeping in mind that the take-up mechanism has a fixed stroke. An increase in the lost motion will have the reverse effect. Due to the interconnection of the presser foot and the wedge 64 an upward movement of the presser foot 105 will cause the wedge to move to the left Figs. 1 and 4, and a downward movement will cause the wedge to move to the right. It will thus be seen that when thicker stock or work is placed in the machine, the presser foot 110 will be raised and the amount of thread measured for the next stitch will be increased. The levers and wedge are so designed that the amount of thread drawn and measured is in accordance with the 115 120 125 130

thickness of the work, so that the correct amount will be automatically drawn and measured for every thickness. This insures that the lock will be set at a uniform distance in the work irrespective of its thickness.

It is sometimes necessary to vary the timing of the opening of the lock independently of the automatic mechanism, for instance, in order to adjust the machine for stitches of different lengths or for preliminary adjustments for the tension of the thread. This can be accomplished by varying the time of the opening of the lock by independently varying the amount of lost motion referred to above. By referring to Fig. 4 it will be seen that if the sleeve 52 is raised the amount of lost motion will be increased, and if lowered decreased. The mechanism can therefore be manually and independently adjusted by adjusting the knurled sleeve 52, this sleeve being locked in adjusted position by means of the lock nut 53.

In order to insure accurate measuring of the thread, a tension device is placed between the lock and the thread supply. In this way the thread is delivered to the lock under tension so that overthrow of thread is prevented. The spring 74 is, however, a comparatively light spring, so that the tension on the thread will only be sufficient to prevent overthrow. It will therefore be seen that in accordance with this invention the thread is locked during the take-up and stitch setting movement of the take-up members and is released by opening the lock, during the latter part of the take up stroke of the take-up members. The actuator for both the take-up device, comprising the take-up members, and for positively opening and permitting closing of the thread lock, is operated from a single cam in the cam wheel 45. The take-up and the thread lock are therefore operated in co-operative relation through means comprising the cam wheel, its levers and the coacting spring 56. The movement given to the movable clamping member of the thread lock will of course be comparatively small so that the thread will be locked as soon as the take-up members start on their thread giving movement. In this way the thread is locked against movement during practically the entire thread giving movement of the take-up device, whereby it is insured that the thread will not be accidentally drawn from the supply by the shuttle or other parts of the stitch forming mechanism. The take-up members have a fixed stroke with a fixed point as the end of the stroke, and by timing the point of opening of the thread-lock, the duration of the releasing action of the lock, and therefore the duration of the thread drawing action or movement of the take-up members, can be varied. By utilizing the take-up

members for drawing the thread, the number of parts are reduced to a minimum resulting in simplicity of construction. The lock is so constructed that it can be easily assembled and disassembled, and all its moving parts are locked so as not to become loose.

While only one embodiment of this invention has been shown and described, it will be obvious that the invention may be embodied in different forms. It is also obvious that various changes may be made in details of construction without departing from this invention, and it is therefore to be understood that this invention is not to be limited to the specific construction shown and described.

Having thus described the invention what is claimed is:

1. In a sewing machine, the combination with stitch forming mechanism, of a take-up device adapted to take up and set the stitch and then measure thread from the supply, a thread-lock separate from but co-operating with said take-up device, and means for operating said take-up device and thread-lock in co-operative relation, constructed to cause said thread-lock to lock the thread during substantially the entire thread giving movement of the take-up device and while the take-up device sets the stitch, and constructed to then cause said thread-lock to release the thread while said take-up device measures sufficient thread from the supply for the next stitch.

2. In a sewing machine, the combination with stitch forming mechanism, of a take-up device having a movement to take up and set the stitch, and a movement to measure thread from the supply, a thread-lock separate from but co-operating with said take-up device, a single actuator for operating said take-up device and said thread-lock in co-operative relation, constructed to permit said thread-lock to lock the thread during substantially the entire thread giving movement of the take-up device and during the movement of said take-up device in setting the stitch, and constructed to cause said thread-lock to release the thread while said take-up device moves to measure sufficient thread from the supply for the next stitch, and automatic controlling means constructed to automatically vary the amount of thread measured in accordance with the thickness of the work.

3. In a sewing machine, the combination of a pair of take-up levers, a gear connected to one of said levers, a gear meshing with said first gear, a thread-lock, and means for operating said second gear having a portion adapted to engage and actuate the thread-lock.

4. A take-up device, comprising a lever with a thread engaging part, a second lever actuated from the first lever, a tension de-

vice, and means connected to the operating means for the second lever for actuating the tension device.

5. A take-up device comprising a lever with a thread engaging part, a second lever with a thread engaging part having a segmental gear attached, an independently mounted gear meshing with said segmental gear, a thread clamp, means for operating said independently mounted gear, having a projection adapted to engage and operate the thread clamp.

6. In a sewing machine, the combination with stitch forming mechanism, of a take-up device adapted to take-up and set the stitch and then measure thread from the supply, a thread-lock separate from but co-operating with said take-up device, and a single cam actuated member for operating said take-up device and thread-lock in co-operative relation, constructed to permit said thread-lock to lock the thread while the take-up device sets the stitch, and constructed to then cause said thread-lock to release the thread while said take-up device measures sufficient thread from the supply for the next stitch.

7. In a sewing machine, the combination with stitch forming mechanism, of a take-up device adapted to take up and set the stitch and measure thread from the supply, a thread-lock separate from said take-up device and comprising a pair of relatively movable thread clamping members, and means for operating said take-up device and said thread-lock in co-operative relation, constructed to cause said thread clamping members to clamp the thread while said take-up device sets the stitch, and constructed to then separate said thread clamping members to release the thread while said take-up device measures sufficient thread from the supply for the next stitch.

8. In a sewing machine, the combination with stitch forming mechanism, of a thread lock comprising a pair of relatively movable thread clamping members, thread measuring means having a fixed stroke, means for operating said thread-lock and said thread measuring means in co-operative relation constructed to separate said thread clamping members to release the thread and permit said thread measuring means to draw from the supply and through said thread-lock sufficient thread to form the next stitch, and automatic controlling means for said thread-lock constructed to cause said thread clamping members to be separated earlier or later during the stroke of said thread measuring means to permit said thread measuring means to measure the thread in accordance with the thickness of the work.

9. In a sewing machine, the combination of thread-controlling mechanism including

a thread-lock adapted to lock and release the thread, means governed automatically by the thickness of the work for controlling said thread-lock to vary the point during the cycle of operations at which the thread is released by said thread-lock, and means for independently varying the point at which the thread is released by said thread-lock as controlled by said controlling means.

10. In a sewing machine, the combination of thread controlling mechanism including a thread-lock adapted to lock and release the thread, an actuator for said thread-lock, means governed automatically by the thickness of the work for varying the point during the cycle of operations at which the thread-lock is opened by said actuator, and means for independently varying the point during the cycle of operations at which the thread-lock is opened by said actuator.

11. In a sewing machine, a thread-lock comprising a thread clamping member, an actuator, an adjustable member positioned between said clamping member and said actuator constructed to cause said actuator to move said clamping member through said adjustable member, said adjustable member being constructed to vary the operation of said clamping member, and a work engaging member connected to said adjustable member.

12. In a sewing machine, a thread-lock comprising a thread clamping member, an actuator for said thread clamping member, an adjustable member between said clamping member and said actuator constructed to engage said clamping member, and a work engaging member connected to said adjustable member to vary the point of engagement, during the stroke of said actuator, of said adjustable member with said clamping member.

13. In a sewing machine, a thread-lock comprising a thread clamping member, an actuator for said thread clamping member, an adjustable wedge between said clamping member and said actuator constructed to engage said clamping member, and a work engaging member connected to said wedge to vary the point of engagement, during the stroke of said actuator, of said wedge with said clamping member.

14. In a sewing machine, the combination of thread measuring means including a thread engaging member, an actuator, means for moving said actuator to engage and actuate said member, means for adjusting said member toward and from said actuator, and means for adjusting said actuator toward and from said member.

15. In a sewing machine, the combination of thread measuring means including a thread engaging member, an actuator movable to engage and actuate said member, means for automatically adjusting said

member and actuator relatively in accordance with the thickness of the work, and means for manually adjusting said member and actuator relatively.

- 5 16. In a sewing machine, thread measuring mechanism including in combination a thread lock, a stitch setting take up separate from said thread lock constructed and operated to draw from the supply and
10 through said thread lock an amount of thread sufficient to form the next stitch, an actuator for said thread lock, and means for

automatically adjusting said actuator and thread lock relatively, constructed to vary the thread locking action of said thread 15 lock in accordance with the thickness of the work.

In testimony whereof I affix my signature in presence of two witnesses.

GEORGE L. CORCORAN.
